DESIGN FOR A UTILITY BOX

Louis Szakacs, Rome, N. Y.

Application March 14, 1945, Serial No. 118,486

Term of patent 7 years

(Cl. D58—11)

To all whom it may concern:

Be it known that I, Louis Szakacs, a citizen of the United States, residing at Rome, in the county of Oneida and State of New York, have invented a new, original, and ornamental Design for a Utility Box, of which the following is a specification, reference being had to the accompanying drawings, forming a part thereof.

In the drawings:

Fig. 1 is a front elevational view of a utility box, showing my new design;

Fig. 2 is a side elevational view thereof;

Fig. 3 is a top plan view of the same.

Fig. 4 is a plan view thereof in open position.

The other side, not shown, is identical with the one shown, and the rear is plain.

I claim:

The ornamental design for a utility box, as shown and described.

LOUIS SZAKACS.
